UNITED STATES PATENT OFFICE.

OLIVER B. McCLINTOCK, OF MINNEAPOLIS, MINNESOTA, ASSIGNOR TO O. B. McCLINTOCK CO., OF MINNEAPOLIS, MINNESOTA, A CORPORATION OF MINNESOTA.

DESIGN FOR A CASING HEAD FOR A THERMOMETER.

Application filed March 11, 1929. Serial No. 30,423. Term of patent 14 years.

To all whom it may concern:

Be it known that I, OLIVER B. McCLINTOCK, a citizen of the United States, residing at Minneapolis, in the county of Hennepin and State of Minnesota, have invented a new, original, and ornamental Design for a Casing Head for a Thermometer, of which the following is a specification, reference being had to the accompanying drawing, forming part thereof.

The figure is a perspective view of a casing head for a thermometer, showing my new design.

I claim:

The ornamental design for a casing head for a thermometer, as shown.

OLIVER B. McCLINTOCK.
